WATER TIGHT RECEPTACLE AND PLUG

Joseph C. Wylie, Glen Ridge, N. J., assignor to
F. H. Lovell & Company, Arlington, N. J., a
corporation of New Jersey

Application February 15, 1930, Serial No. 428,849

10 Claims. (Cl. 173—338)

My invention relates to the art of electrical connectors and particularly to socket-plugtype connectors for use on shipboard or other locations where a fluid-tight construction is required.

5 Primarily the invention has for its object to provide a plug and receptacle of such construction that water can be kept from entering the conduit, box and conduit and of such construction that it will keep water of condensation within 10 in the conduit or conduit box from entering the receptacle and engaging the contacts therein.

Further, it is an object to provide a plug and receptacle for use in conduit boxes which will prevent drafts through the conduits.

15 Further, it is an object to provide a plug receptacle having an insulating body molded in one piece within a metallic threaded mantle by means of which it may be screwed into a conduit box, the body having conducting lugs molded in place 20 and containing the necessary contacts, springs and screws to adapt the receptacle for its purposes.

Further, it is an object to provide the receptacle body with recesses for the contact springs, 25 thereby to maintain their location and prevent the springs being turned on their rivets into contact one with another when the plug is withdrawn, thus eliminating possibility of short-circuiting the contacts when the plug is not in place.

30 Further, an object is to provide a plug and receptacle in which the contacts are not directly exposed if the plug is pulled.

Other objects will in part be obvious and in part be pointed out hereinafter.

35 To the attainment of the aforesaid objects and ends, my invention consists in the novel details of construction and in the combination, connection and arrangement of parts, hereinafter more fully described and then pointed out in the claims.

40 In the accompanying drawings, showing illustrative embodiments of the invention,

Figure 1 is a vertical longitudinal half-section and half-elevation of the invention in use, the conduit box being shown in section,

45 Figure 2 is a central vertical longitudinal section of the receptacle body, its mantle and contacts.

Figure 3 is an elevation of the closed end of 50 the body shown in Figure 2,

Figure 4 is an elevation of the open end of the body shown in Figure 2,

Figure 5 is a side elevation of the plug,

Figure 6 is an end elevation of the plug,

55 Figure 7 is a vertical longitudinal section of

the metallic body of the plug which carries the contact-carrying body shown in Figure 8,

Figure 8 is a vertical longitudinal section of the insulating contact-carrying body of the plug, 60 Figures 9 and 10 are end elevations of the body shown in Figure 8.

In the drawings, in which like numerals of reference indicate like parts in all the references, 65 1 represents the body of the shell which is made of suitable insulating material such as "Bakelite" for example. The body of the shell, which is of tubular form open at one end, is provided internally with a flat face 2 and opposed recesses 3, the latter being designed to receive the contact springs 9.

70 Binding posts 4 are molded in the bottom 5 of the body 1, the body 1 being provided with a rib 6 to separate the binding posts 4 and prevent short-circuiting between the binding posts and the portions of the contact springs 9 that are 75 riveted thereto when the conductor wires are connected.

The body 1 is preferably molded of one piece and within a metallic mantle 7 threaded externally to screw into the conduit box cover 31 hereinafter again referred to. The contact springs 9 are riveted at 8 to the binding posts 4.

80 The plug is composed of a molded body 10 of suitable insulation such as "Bakelite" for example, the body 10 having a passage 11 through the same which is of approximately rectangular cross section, the upper portion of which is flared as at 12 to permit the convenient passage of conductor wires. The neck portion 13 of the body 10 is externally threaded as at 14. The 85

plug body 10 is provided with a flattened portion 15 to cooperate with the flattened portion 2 of the receptacle and thus insure proper mating of the parts. Contact spring-receiving slots 16 are also provided and these slots have ribs 17, and 90 embracing which and located in a countersunk position as it were are the contact binding posts 18 which cooperate with the springs 9 of the plug receptacle when the parts are assembled.

A metallic carrier 19 is provided for the plug 95 body, the carrier having a threaded recess 20 to receive the threads 14 of the neck of the plug body and secure a rubber gasket 24 between the flange 22 of the carrier 19 and the neck of the body 10.

100 The metallic carrier 19 has a collar portion 21 and is threaded on the outside as at 23 to receive the sealing cap 26, a packing ring 25 being inserted in the end of the carrier 19. The packing ring is designed to be compressed by 110

screwing on the cap 26 to effect a seal around the flexible cable which passes through the plug and carries the conductors which have their ends fastened to the contact-binding posts 18.

5 A milled clamping nut 27 is threaded onto the mantle 7 and abuts the flanges of the carrier 19 in order to squeeze the packing and effect a liquid-tight joint. The clamping nut 27 has a portion 28 to cooperate with the collar portion 21, 10 and another portion 29 to cooperate with the flange 22 as best shown in Figure 1 of the drawings.

By reference to Figure 1 it will be seen that 30 designates the conduit box having a cover 31 which is sealed fluid-tight by a gasket 32. The conduit is designated by the character 33 and the conductors 34 which pass from the conduit into the conduit box and are secured to the binding posts 4 and indicated by the numeral 34.

20 The flexible cable from the contact-binding posts 18 to the portable lamp or other electrical appliance is designated by the numeral 35.

It should, of course, be understood that the conduit box constitutes no part of the present 25 invention and is illustrated merely to show a use of the invention.

It will be observed that when the parts constituting the invention are assembled in the manner indicated in Figure 1 of the drawings, it will 30 be quite impossible for fluids to enter the conduit box via the plug or plug receptacle because of effective sealing which has been provided. When it is desired to disconnect the plug it is only necessary to unscrew the milled clamping 35 nut 27 from the mantle when the plug can be pulled out of the plug receptacle. When the plug has been pulled out of the plug receptacle water will still be prevented from entering the conduit box by reason of the sealing of the cap of that box and the fitting of the threaded mantle into the cover, it being understood that the mantle after it has been threaded into the cover is preferably soldered around the threads to insure a fluid-tight joint.

40 45 By providing the flat faces 2 and 15 it will be impossible to insert the plug into the receptacle in any but the correct position, i. e., the position where the recesses provided by the slots 16 of the plug will be in a position to receive the contact springs 9.

50 Further, it is to be noted that the flat face 2 on the side of the body 1 which cooperates with a registering flattened portion 15 of the plug body 10, serves to prevent the reversing of the polarity of the device.

Having thus described my said invention, what I claim and desire to secure by Letters Patent is:

1. In connectors, a plug-receptacle comprising 60 a hollow body of non-conducting material and open at one end only, said body having binding posts sealed in the other end, one end of said binding posts being located inside the body and the other end outside the body, means to secure 65 terminal wires to the outside ends of said posts, contact springs secured to said posts within the body and a threaded mantle on the outside of said body, substantially as specified.

70 75 2. In connectors, a plug-receptacle comprising a hollow body of non-conducting material and open at one end only, said body having binding posts sealed in the other end, one end of said binding post being located inside the body and the other end outside the body, means to secure 80 terminal wires to the outside ends of said posts,

85 contact springs secured to said posts within the body and a threaded mantle on the outside of said body, said body having recesses in its inner wall to receive said contact springs, substantially as specified.

90 95 3. In connectors, a plug-receptacle comprising a hollow body of non-conducting material and open at one end only, said body having binding posts sealed in the other end, one end of said binding posts being located inside the body and the other end outside the body, means to secure terminal wires to the outside ends of said posts, contact springs secured to said posts within the body and a threaded mantle on the outside of said body, and means to hold said contact springs against short-circuiting when a plug, with which the receptacle is adapted to cooperate, is withdrawn, substantially as specified.

100 105 4. In connectors, a plug-receptacle comprising a chambered body with binding posts molded in place, contact springs carried by said posts and located within the chamber of said body, and connecting screws carried by said posts outside the chamber, in combination with a plug, the latter having a portion with terminal contact lugs adapted to enter said receptacle and cooperate with said contact springs, and means to produce a water-tight joint between said plug and said receptacle and between said plug and a cable passing through the same, substantially as specified.

110 115 5. In connectors, a plug-receptacle comprising a chambered body with binding posts molded in place, contact springs carried by said posts and located within the chamber of said body, connecting screws carried by said posts outside the chamber, said body including a rib between the binding posts, in combination with a plug, the latter having a portion with terminal contact lugs adapted to enter said receptacle and co- 120 operate with said contact springs, and means to produce a water-tight joint between said plug and said receptacle and between said plug and a cable passing through the same, substantially as specified.

125 130 6. In connectors, a plug-receptacle comprising a hollow body of non-conducting material and open at one end only, said body having binding posts sealed in the other end, one end of said binding posts being located inside the body and the other end outside the body, means to secure terminal wires to the outside ends of said posts, contact springs secured to said posts within the body and a threaded mantle on the outside of said body, in combination with a plug, the latter having a portion with terminal contact lugs adapted to enter said receptacle and cooperate with said contact springs, and means to produce a water-tight joint between said plug and said receptacle and between said plug and a cable passing through the same, substantially as specified.

135 140 7. In connectors, a plug-receptacle comprising a hollow body of non-conducting material and open at one end only, said body having binding posts sealed in the other end, one end of said binding posts being located inside the body and the other end outside the body, means to secure terminal wires to the outside ends of said posts, contact springs secured to said posts within the body and a threaded mantle on the outside of said body, said body having recesses in its inner wall to receive said contact springs, in combination with a plug, the latter having a portion with terminal contact lugs adapted to enter said re- 145 150

ceptacle and cooperate with said contact, springs and means to produce a water-tight joint between said plug and said receptacle and between said plug and a cable passing through the same, substantially as specified.

8. In connectors, a plug-receptacle comprising a hollow body of non-conducting material and open at one end only, said body having binding posts sealed in the other end, one end of said binding posts being located inside the body and the other end outside the body, means to secure terminal wires to the outside ends of said posts, contact springs secured to said posts within the body and a threaded mantle on the outside of said body, means to hold said contact springs against short-circuiting when a plug, with which the receptacle is adapted to cooperate, is withdrawn, in combination with a plug, the latter having a portion with terminal contact lugs adapted to enter said receptacle and cooperate with said contact springs, and means to produce a water-tight joint between said plug and said receptacle and between said plug and a cable passing through the same, substantially as specified.

25 9. In connectors, a plug-receptacle comprising a hollow body of non-conducting material and open at one end only, said body having binding posts, means to secure terminal wires to the said posts, contact springs secured to said posts and a threaded mantle on the outside of said body, means to hold said contact springs against short-circuiting when a plug, with which the receptacle is adapted to cooperate, is withdrawn, combined with a plug consisting of a non-conducting body having a cable passageway through the same and provided with a slotted skirt, contact posts recessed in the slots of said skirt, said slots receiv-

ing said contact springs when plug and receptacle are assembled, a flanged carrier for said non-conducting body, a gasket on said non-conducting body adjacent the flange of said carrier to engage the end of said receptacle when plug and receptacle are assembled, a flanged nut on said carrier to mate with said threaded mantle and effect a fluid-tight joint between plug and receptacle, and packing means carried by said carrier to seal a cable in its passage for the purpose specified.

10. In connectors, a plug-receptacle comprising a one-piece chambered body with binding posts molded in place, contact members carried by said binding posts and located within the chamber of the body and connecting screws carried by said binding posts outside the chamber, a threaded mantle surrounding said chambered body and constituting an integral structure therewith, combined with a plug consisting of a non-conducting body having a cable passageway through the same and provided with a slotted skirt, contact posts recessed in the slots of said skirt, a flanged carrier for said non-conducting body, a gasket on said non-conducting body adjacent the flange of said carrier to engage the end of said receptacle when plug and receptacle are assembled, a flanged nut on said carrier to mate with said threaded mantle and effect a fluid-tight joint between plug and receptacle, packing means carried by said carrier to seal a cable in its passage through said carrier, and means forming a part of the plug and receptacle respectively insuring a mating of plug and receptacle in one position only, substantially as specified.
